LADLE STOPPER CONTROL APPARATUS

Richard J. Carleton, Jr., Chagrin Falls, Ohio, assignor, by mesne assignments, to Blaw-Knox Company, Pittsburgh, Pa., a corporation of New Jersey

Application November 1, 1951, Serial No. 254,361

7 Claims. (Cl. 22—35)

This invention relates to means for controlling ladle stoppers employed in conjunction with the nozzles of ladles used in pouring molten metal, especially molten steel, and relates more particularly to a means for operating a power driven stopper which can be controlled by an operator who may move about freely to observe the pouring from the best vantage point.

In the pouring of steel ingots, a ladle having a capacity which may be as high as about 200 tons or more of molten steel is provided with a nozzle, in the bottom of the ladle. The ladle is suspended above the ingot mold into which the molten steel is to be poured and the stopper, which is pressed down against the nozzle in the closed position, is raised to permit the steel to flow into the mold.

If the steel is poured into the mold too rapidly, gas becomes entrapped in the mold and a poor ingot results. Also, if the steel is poured too rapidly at the beginning or the end of the pouring, considerable splashing occurs which results in a loss of steel and endangers the operating personnel.

If the pouring is carried out too slowly, metal which normally splashes against the interior of the mold, at the beginning of the pouring, solidifies before the level of the poured metal in the mold rises to remelt the splashed metal. The solidified metal forms scales on the outside of the ingot. The removal of such scales requires additional scarfing, chipping and grinding in the cleaning of the ingot surface before it can be used for subsequent operations.

It is, therefore, desirable to have a means by which the pouring may be controlled so that the above noted and other difficulties will not result. A desirable type of control is one in which the pouring can be regulated or controlled to permit relatively slow pouring at the very beginning and at the end of the pouring and relatively rapid pouring intermediate the beginning and the end.

The practice has been to operate the stopper by means of an external linkage system connected to a manually operated lever. However, because of the weight of the stopper, even with the mechanical advantage of the linkage system, the operator has been required to exert a considerable force, i. e. in the neighborhood of 150 lbs.

Because of the required exertion necessary to change the stopper position and particularly to close the nozzle, accurate control of the stopper to regulate the pouring rate has been difficult. The degree of control of the stopper has been dependent in large measure on the vigor and freedom from fatigue of the operator.

At the end of the pouring of one ingot, the nozzle is closed by moving the stopper down. If the nozzle is not completely closed, molten steel continues to leak or dribble from the nozzle as the ladle is moved from one mold to another. If such leakage is sufficiently heavy, there may be a loss, for example, of as much as two ingots of steel in a single heat, i. e. in a single ladle load which may be capable of pouring 45 to 50 ingots. In addition to the loss of steel, there is the expense in time and labor

2

of hand cleaning the dribbled steel from the tops and sides of the mold and from the platforms of the cars on which the molds are carried. Furthermore, the splashing of the steel from a leaking nozzle is a great danger to the operator of the stopper lever. If the leaking becomes too heavy the operator may be obliged to release his grip on the stopper control lever with the result that a large amount of steel in the ladle is lost.

Especially because of these leakage problems, it is particularly desirable to have a safely and surely operable means for applying sufficient pressure to the stopper to close the nozzle effectively whenever desired.

In pouring an ingot, it is also desirable to control the height of the ingot in the mold to obtain products of uniform size and weight. In order to obtain the desired height, a chalk line or equivalent is customarily used to indicate on the inside of the mold such desired height prior to the pouring. Then as the level of the ingot reaches the chalk line, the operator of the stopper is expected to close it. The decision to close the nozzle, therefore, is based upon visual observation by the pourer, i. e. the operator, but with the manual control, his movements are limited, in that he cannot move beyond arm's length of the stopper lever. Under such circumstances, the chalk line may not always be visible to the pourer, especially if the ingot smoke and steam which are given off in the pouring should travel in a direction to obscure his vision. If he were able to move about freely, he could avoid the obscuring smoke, observe the chalk line and shut off the flow at the proper time. Furthermore, with the manual stopper means, it is difficult to effect the closing rapidly at the desired moment when the steel reaches the chalk line, and with sufficient pressure to prevent a leak from the nozzle which will add further steel above the line.

While there has been some recognition of the desirability of substituting mechanical power for the manual operation of stoppers, no fully satisfactory apparatus has heretofore been available. For instance, devices have been proposed for control from the crane cab, but without recognition of the need for better instead of poorer visual observation than is available to a pourer operating a manual lever. In such devices, electrically powered means suggested for driving the stopper require an impractically large and heavy motor on the ladle. Another arrangement, controlled as above, contemplates a compressed air cylinder for displacing the stopper. Such device, however, is inherently incapable of controlling the degree or extent of stopper opening; it is even less accurate in controlling the pouring rate than manual operation, because the piston in the air cylinder cannot be held at a selectable intermediate position but can only be arrested at a single prefixed point. As successive ingots are poured from a ladle, the amount of molten steel in the ladle decreases, with corresponding decrease of the head or pressure on the issuing metal, so that the stopper must be opened progressively wider to obtain the same rate of flow. It has thus now been appreciated that an arrangement which only permits the stopper to open the same distance each time cannot give a uniform rate of flow for successive ingots and also cannot provide variation of the rate of flow during the pouring of a single ingot.

In the present invention, a principal object has been to provide a power system for a ladle stopper which obviates or reduces difficulties of the sort outlined above in relation to manual and other prior devices, and which may be conveniently controlled from a wide range of positions, indeed from a portable apparatus, so that the operator, while retaining full control of the power means for the stopper, is able not only to move out of danger of

fumes or splashing metal, but also to move about freely at all times and thus to obtain the best vantage point, despite smoke, steam and other obstacles, for observation of the pouring and of the chalk line or other ingot height indication.

A still further object of the power control system of this invention is to provide new and improved apparatus which can be easily and rapidly positioned on the side of the ladle, which is of relatively light construction and can exert forces sufficiently great to effectively close the stopper, and which can be controlled so as to move the stopper slowly or rapidly up or down or to hold it in an intermediate position between a fully opened and a fully closed position.

A still further object of this invention is to provide a system which requires relatively little exertion upon the part of the operator and provides a great degree of safety.

Another object is speedier and more accurate pouring practice with greater yield at reduced cost and improved ingot quality resulting from good control of the pouring rate.

By way of introduction, a brief outline may be given here of some elements of the invention, which essentially comprises a power apparatus to be connected to and to actuate a ladle stopper and control means to operate the power apparatus. The power apparatus includes a hydraulic system employing a substantially non-compressible fluid and the control means includes an electrical system for selectively operating the hydraulic system whereby the stopper may be moved to and maintained in any desired position within its operative range. The electrical system includes switch means which may be operated from a portable apparatus whereby the operator is free to move relative to the ladle and associated equipment.

For a more complete disclosure of the invention and its further novel and advantageous features, reference is made to the following description, and to the accompanying drawings wherein:

Fig. 1 is a schematic arrangement of apparatus embodying this invention with parts in section to indicate specific structure thereof;

Fig. 2 is a side view of a hydraulic cylinder and related parts employed in the apparatus, portions being cut away to show details;

Fig. 3 is a view of the hydraulic cylinder and related parts taken along the line 3—3 in Fig. 2;

Fig. 4 is a cross sectional view of the hydraulic cylinder assembly taken along the line 4—4 in Fig. 2; and

Fig. 5 is a diagram of the automatic control and hydraulic power system for the hydraulic cylinder.

Referring to Fig. 1, a ladle 10 having a suitable refractory lining 11 is provided with a bottom orifice or nozzle 12. The nozzle is closed by a stopper 13 which may be formed of a vertical steel rod 15 having a tip 16 of refractory material and a plurality of refractory collars or sleeves 17 arranged in successive abutting or interlocking relationship with each other between the tip and a retaining nut 18, to provide the stopper rod 15 with a protective covering so that it will not melt when the ladle is filled with molten steel.

The upper end of the stopper 15 is provided with means for rigidly attaching a cross-head member 20 in any desired manner such as by providing a hole in the cross-head 20 of suitable size to receive the end of rod 15, the cross-head being held in place by nuts 21 threaded on the rod 15 and disposed in abutting engagement with the top and bottom sides thereof. The cross-head, which is horizontally disposed, extends outwardly beyond the lip 22 of the ladle 10 and has a slide or guide rod 23 rigidly fixed adjacent the end 25. The tapered upper end of the slide rod 23 is received in a hole formed in the cross-head 20 and is locked in position by wedge key 24.

The slide rod 23 which is adapted to be disposed substantially vertical and parallel to the stopper 13 is supported in slidable engagement with a guide or barrel member 26 which is mounted on the side of the ladle 10.

The slide rod may be a single member, or a composite member as shown in Fig. 1, and should have means to prevent its rotation with respect to the barrel 26. If the slide rod and cross-head rotated about the axis of the slide rod, the stopper 13 would become misaligned with the nozzle and thereby be rendered ineffective in stopping the nozzle. A convenient means for preventing the rotation of the slide rod 23 is to provide key 29 on the rod adapted to be received in a mating keyway on the inside of the slide barrel 26.

The barrel or guide 26 is mounted on the side of the ladle by means of a pivot mounting at 27 to bracket 28 fixed to the outer shell of the ladle 10. The lower end of the slide barrel 26 is held in position by an adjustable means by which the angular disposition of the sleeve may be adjusted. The adjustable means shown may include a shaft 31 suitably threaded in a collar on the slide barrel 26 and rotatably mounted to the side of the arms 32 will effect an adjustment of the barrel 26.

The lower end 33 of the slide rod 23 may be provided with the usual mechanical linkage for manual operation of the stopper for use in the event of a failure of power for the power control device to be described. The mechanical linkage consists of a link 35, pivotally mounted at 36 to a bracket near the lower end of the slide barrel 26 and pivotally mounted at its other end at 37 to a cross sleeve member 38, the member 38 being pivotally mounted at 40 to the lower end 33 of the slide rod 23. The sleeve member 38 is adapted to receive a lever 41 for manual operation, as shown in dash lines in Fig. 1.

From the above description, it will be appreciated that a movement of the slide rod 23 upward causes the stopper 13 to be raised thereby opening the nozzle 12 and permitting the molten steel 14 to flow from the ladle. Conversely, a movement of the slide rod downward causes the stopper to be lowered thereby closing the nozzle and arresting the flow of molten steel from the ladle.

The parts thus far described are included in the usual stopper apparatus and adjustment of the stopper to the open or closed position is effected by the manual operation of the lever member 41 by an operator, i. e. pourer, standing on platform 42.

The ladle, 10, shown in Fig. 1, is filled with molten steel and has been moved, by means such as a crane, into position over a mold 43 which is to receive the steel. The molds are customarily carried on flat cars 45 which are supported on trackways 46.

In the apparatus of this invention, it is contemplated to raise and lower the stopper by a double-acting hydraulic cylinder assembly 51 removably attached to standard stopper actuating apparatus. For this purpose, the upper end of the cylinder 51, as shown in Figs. 1, 2 and 3, is connected to a bracket 47 fixed on the slide barrel 26. Piston rod 52, extending from a suitable piston 50 (Fig. 5) in the cylinder 51 and thus slidably mounted in the cylinder, is attached to a bracket 48 fixed on the lower part 33 of the slide rod 26 adjacent the pivot connection with the member 38. The cylinder is disposed so that a downward movement of the piston rod 52 causes a downward movement of the slide rod 23 and the stopper 13, and an upward movement of the piston rod 52 moves the slide rod 23 and the stopper 13 upward.

A more complete description of the means of attaching the cylinder 51 will be given after the operation of the cylinder and the hydraulic power system and electrical control therefor has been detailed.

Referring to Fig. 5, the hydraulic power system includes the piston 50, which is reciprocable in the cylinder 51 and to which the piston rod 52 is attached, suitable

glands or packing being utilized, if desired, around the piston rod to prevent leakage as it extends through the end of the cylinder. Ports 55 and 56 are provided adjacent to the ends of cylinder 51, the ports being connected by lines, i. e. pipe or tubing, 57 and 58 (as shown schematically in Fig. 5) to one side of a valve 60, which is conveniently a four-way, three-position valve, viz. a reversing valve with a central neutral position.

A substantially non-compressible fluid, i. e. a liquid such as oil, may be supplied under pressure to the other side of the valve by means of pump 61 which draws fluid from reservoir 62, through line 63 and pumps it under pressure through line 64. Line 66 is connected to the valve 60 to receive exhaust fluid and return it to the reservoir 62.

The valve 60 may be provided with a slidable plug or core member 67 having pairs of bores disposed at three portions A, B and C to direct the flow of fluid to the cylinder for actuation of the piston in the manner to be described. For clarity of illustration the portions A, B and C are shown at fully separated localities, but in practice they can be disposed in successively overlapping positions, as is generally conventional in valve construction, to shorten the stroke of the plug.

When not positively actuated, the valve plug 67 is maintained in the position shown in Fig. 5 by springs 70. In this condition, with the portion C of the plug 67 in operative position, the lines 65 and 66 are connected by U-shaped bore 71 so that the pumped fluid circulates back to the reservoir and movement of fluid into or out of the cylinder is blocked; in consequence the piston is held in the cylinder in the position to which it was last moved.

To move the valve plug 67 so that the A or B portions are in operative position, solenoids 72 and 73 are provided, and are arranged for actuation by manual switch controlled circuits, described below.

A dump valve 85 is also provided so that when the apparatus is not in operation, fluid may be exhausted from both sides of the piston through ports 55, 56, lines 57, 58, to branch lines 86, 87, then through bores 88, 89, formed in slidable core 84 of the dump valve, and thence through line 91 to the reservoir 62. The core 84 of the dump valve 85 is adapted to be maintained in the open position by spring means 90, but while the apparatus is in operation, it is moved to and held in the closed position shown in Fig. 5, by energization of a solenoid 82.

Electric current, either A. C. or D. C., may be supplied to the solenoid circuits through lines, i. e. conductors, 75 and 76 from a suitable source. When the "off-on" switch 77 is moved to close the circuit from line 75 through contacts 78, 80 (of the switch 77), line 81, dump valve solenoid 82 and line 83 which is connected to line 76, the solenoid 82 is energized causing the rod 79 and the core member 84 to which the rod is attached to move upward, against the pressure of the spring 90, to the closed position shown in Fig. 5.

The closing of the switch 77 also may be used to start the pump motor 68 by completing the circuit through line 75, contacts 78, 80, lines 81, 93 and 94 to the motor and thence via line 99 back to line 76. However, it will be understood that if desired, a separate circuit (not shown) of conventional character can be used to energize the motor, so that it may be controlled separately from the dump valve 85.

As noted, when the "off-on" switch 77 is open, the solenoid 82 is not actuated and the dump valve 85 is in the open position. With the dump valve open, fluid from both sides of the piston may be exhausted through branch lines 86 and 87, dump valve bores 88, 90 and into line 91 which returns the fluid to the reservoir.

When the switch 77 is in the closed or "on" position the circuits to energize solenoids 72 and 73 may thereafter be closed.

In order to lower the piston 50 in the cylinder 51, and thereby close the nozzle 13 (Fig. 1), the "down" switch 92 is moved to close the circuit through lines 81, 93, contacts 95, 96 (of the switch 92), line 97, solenoid 72, and line 98 to line 76. The closing of the circuit energizes the solenoid 72 causing rod 100 and the valve plug 67 to which rod 100 is connected to move to the right, as viewed in Fig. 5 so that the A portion of the plug 67 is in operative position. When the A portion is in operative position, the bore 101 connects the pressure line 65 with the line 57 to deliver fluid under pressure to the upper end of the cylinder 51 and the bore 102 connects the line 58 from the lower end of the cylinder to the exhaust line 66. In this position of the valve 60, the piston 50 and the piston rod 52 will move down until the switch 92 is opened or until the tip 16 of the stopper 13 is seated tightly against the nozzle 12.

A relief valve 103 may be connected between lines 65 and 66 to bleed off excess pressure, for example when the stopper 13, which is actuated by the piston rod 52, is seated against the nozzle. The relief valve may be of standard type which may be adjusted to permit a desirable maximum amount of pressure to be exerted safely in the cylinder 51, i. e. without failure of the mechanical parts of the cylinder or other equipment.

To raise the piston 50 in the cylinder 51 and thereby raise the stopper to open the nozzle, the "up" switch 105 is closed to complete the circuit through lines 81, 93, contacts 106, 107 (of the switch 105), line 108, solenoid 73, and line 110 to line 76. The solenoid 73 is thus energized by the closing of the switch 105, causing rod 111 and the valve plug 67, to which rod 111 is connected, to move to the left, as viewed in Fig. 5. When the plug 67 is moved to the left, the B portion of the plug is brought into operative position, so that the fluid pressure line 65 is connected through bore 112 and line 58 to deliver fluid under pressure to the lower end of the cylinder 51 to force the piston 50 upward. Fluid is exhausted from the upper part of the cylinder through line 57 and bore 113 to exhaust line 66.

The piston will continue to move upward in the cylinder 51 until the "up" switch 105 is opened or the piston reaches the upper end of the cylinder or until the piston assembly reaches some other mechanical abutment. If the piston is stopped by any such abutment, the relief valve 103 will operate automatically to prevent the exerted pressure from exceeding the maximum mentioned above, so as to prevent damage to the mechanism. An adjustable nut 150 threaded on rod 23 is adapted to abut the lower end 151 of the slide barrel 26 and therefore may be used to limit upward movement of the piston, i. e. at a selected uppermost position.

If it is desired to arrest the upward or downward movement of the piston at a given intermediate point, switches 92 and 105 are opened (in practice one of them will already be open and the other will now be opened by the operator) so that the circuits for solenoids 72 and 73 are both broken. The switch 77 is maintained in the closed position so that the dump valve 85 remains closed. In this condition, which is that shown in Fig. 5, the valve plug 67 is immediately moved by the springs 70 to neutral, where the C portion of the valve plug is in operative position. The U-shaped bore 71 connects lines 65 and 66 so that the fluid under pressure returns directly to the reservoir. The passage of fluid through lines 57 and 58 is now blocked by both the valves 60 and 85 so that there is no movement of fluid into or out of the cylinder and the piston is held by the fluid in the position to which it had been moved before the return of the valve plug 67 to neutral.

Fig. 1 illustrates schematically the preferred physical disposition of the electrically operated hydraulic power system in the combination of this invention. It has been found desirable to position the motor 68, pump 61, res-

ervoir 62, the valve 60, dump valve 85 and the relief valve 103 in the cab 116 of the overhead crane (not shown) which suspends and moves the ladle 10 or on some other suitable supporting means for supporting this hydraulic system for relative movement, at least generally, with the ladle, e. g. above, along or beside the platform 42. The lines 57 and 58 to the ports 55 and 56 of the hydraulic cylinder 51 may be flexible hoses extending from the cab 116 or other supporting means to the cylinder 51. A portable switch box 117 containing switches 77, 92 and 105 is provided with push buttons 77a, 92a and 105a, respectively, which may be manipulated by an operator carrying the box and moving freely about on the platform 42. The switch box 117 is operatively connected to the hydraulic power system in the crane cab 116 by a flexible cable 118 containing related portions of the wiring shown in Fig. 5. If desired, suitable reels (not shown) may be provided on the cab for the hoses 57, 58 and the cable 118, to facilitate extension and retraction of these lines.

Reference is now made to Figs. 1, 2 and 3 which illustrate the hydraulic cylinder 51 and the means for removably attaching it in operative position. A clevis or bifurcated bracket 120 is permanently fixed on the upper end 119 of the cylinder 51, and has a pin 121 suitably fixed between its arms, i. e. parallel to and spaced from the base of the clevis 120. Another clevis 122 is integrally formed or permanently fixed on the outer or lower end of the piston rod 52 and is provided with axially aligned holes 123 (see Fig. 5) in its arms.

The bracket 47 which is attached to the slide rod barrel 26 has an upwardly disposed hook 125 defining a slot 126 sufficiently large to receive the pin 121 of the upper clevis 120.

To attach the cylinder 51 in operative position, the clevis pin 121 is slipped down into the slot 126 while the cylinder is held at about a 45° angle to the vertical. After the pin 121 is seated in slot 126, the lower end of the cylinder is moved or rocked downward, bringing the cylinder toward the vertical position for connection of the piston rod clevis 122 to the bracket 48 as described below.

The bracket 48 is fixed to the lower end 33 of the guide rod 23 (which moves the ladle stopper) by any suitable means, such as the U-shaped bolts 127 which embrace the guide rod (see Fig. 4). The ends of the bolts 127 extend through holes in the back of the bracket 48 and have nuts 128 threaded thereon to hold the bracket 48 in place. A hole 130 (shown in dash lines in Fig. 2) is formed near the outer end of the bracket 48 and is substantially the same size as the axially aligned holes 123 in the piston rod clevis 122. Projecting pins or studs 131 are fixed to the bracket 48 parallel to each other and in horizontally spaced relation to the hole 130, there being a pair of such pins projecting from each vertical face of the bracket alongside of the hole.

After the pin 121 of the upper clevis 120 has been seated in slot 126 of the upper bracket and the lower end of the cylinder 51 has been rocked down into a nearly vertical position, the piston rod 52 may be pressed into the cylinder 51 to permit the lower ends 132 of the clevis 122 to pass above the outer pins 131 on the bracket 48. When the clevis 122 is centered over the hole 130 of the bracket 48, and the cylinder is thus truly vertical, the clevis may be pulled down so that it straddles the bracket with its arms passing between the paired pins 131 on each side and so that the holes 123 in the clevis 122 are in axial alignment with the hole 130 in the bracket, the pins 131 being provided for guiding the clevis 122 into operative position. A draw pin 133, which may be attached to the bracket 48 by a chain 135 to prevent loss, is pushed through the aligned holes 123 and 130 thereby connecting the piston rod 52 to the guide rod 23. The outer surface 136 of the hook 125 on the upper bracket 47 is curved and shaped so that clevis 120 can be inserted and

the cylinder rocked downward as described and so that when the cylinder 51 is in the vertical operative position shown in Figs. 2 and 3, there is only a slight clearance between the base of the clevis 120 (e. g. the head of the cylinder) and the surface. By shaping the hook 125 as shown, the pin 121 cannot slip out of the slot 126 while the cylinder is in the vertical position. At the lower end of the assembly the pin 133 and the straddling position of the clevis 122 prevent any lateral movement of the clevis when it is in operative position.

In order to remove the cylinder 51 from operative engagement, the pin 133 is withdrawn from the holes 123 and 130, and the piston rod 52 is pushed upward so that the ends 132 of the clevis 122 are above the pins 131. With the lower clevis 122 clear of the pins 131, the lower end of the cylinder may be swung upward in an arc until the cylinder is at an angle of about 45°. In that position, the pin 121 between the arms of the upper clevis 120 may be slipped out of the slot 126 in bracket 47 so that the cylinder is disengaged from slide barrel 26 of the stopper actuating apparatus.

It will be appreciated that, even though the attachment and detachment of the cylinder 51 can be achieved rapidly and with great ease, the connections are substantially free from looseness or play and are not subject to accidental disengagement.

It has been found, for example, that a hydraulic cylinder weighing as little as 30 lbs. is capable of delivering 5 to 10 H. P., which is considerably in excess of the power that could be exerted by manual operation. Thus, a source of large power can be used (if desired) with a unit light enough to be easily attached and removed, although with stopper arrangements of presently conventional structure, cylinders delivering up to 3 H. P. have been found adequate. In all cases, superior results are obtained, for instance in that the stopper 13 can be closed very tightly so that dribbling is substantially eliminated. Likewise because of the greater power which may very easily and conveniently be obtained with this apparatus, the ruggedness and strength of the stopper assembly may be increased, it being no longer necessary to keep such assembly of light weight for convenience of manual operation. A stopper assembly with such heavier construction permits greater closing pressure to be exerted and also provides greater rigidity of structure in the assembly so that mechanical failure and misalignment of the parts are minimized. Pressure regulating means, such as the relief valve 103, cooperate in permitting safe realization of maximum power and maximum closing force, for attainment of the advantages described above.

Breakaway couplings may be provided in the hose lines 57 and 58 to permit instantaneous disconnection of these oil supply conduits from the cylinder. The assemblies for such couplings are best shown in Figs. 2, 3 and 4 and include frame brackets 136 which are fixed to and extend rectangularly from the cylinder 51 adjacent the ends thereof, conveniently at the ports 55 and 56. Collars 137, welded or otherwise fixed to each of the brackets 136, are axially aligned and are adapted to receive axially aligned swivel bars 138. The swivel bars 138 are welded to a plate 140 to support the plate pivotally, intermediate the collar members 137. Spacer sleeve members 141, through which the swivel bars 138 are passed, maintain the plate 140 in position between the collar members 137. Washers 142 and cotter pins 143 may be provided at the ends of the swivel bars 138 to maintain the bars in fixed axial position with respect to the collars 137.

Short lengths of flexible hose 57a and 58a are connected at one of their ends to the ports 55 and 56 respectively, the other end of each of the hoses being connected to a receiving plug 145. The plugs 145 are attached to one side of the plate 140, for example by collars 146 held with appropriate securing means such as indicated at 147.

Hose couplings 148, which together with the receiving plugs 145 form the breakaway couplings, are fixed on the ends of the hose lines 57 and 58. The plate 140 is formed with apertures 150, one aperture being shown in dash lines in Fig. 4, through which the couplings 148 may be inserted to make connection with the receiving plugs 145. The breakaway couplings may be arranged to be disconnected by a straight pull of about 60 lbs. on the hose lines 57 and 58. The swivel mounting of plate 140 is provided to permit the operator to exert a straight pull from any angle on the platform in that when a pull is exerted on the hose lines, the plate 140 automatically swivels to a position at right angles to the lines. The couplings 148 and receiving plugs 145 are self-sealing upon disconnection so that there is no leakage of the hydraulic fluid when they are uncoupled from each other. This type of breakaway coupling is well known and because their structure forms no part of this invention, no further description of them is included.

From the foregoing description, it will be understood that to operate the apparatus, the ladle which has been filled with steel is brought into position over the mold, alongside the platform. The ladle pouring operator standing on the platform connects the cylinder 51, which may be stored on the platform, in operative engagement with the barrel member 26 and the slide rod 23. The operator reaches up on the lower side of the crane cab 116 and pulls down the hydraulic hoses 57 and 58 and connects the breakaway couplings 148 to the cylinder 51. He then pulls down the electric switch box 117 on the end of the flexible cable 118. By pressing the button 77a the motor 68 is energized and the dump valve 85 is closed. Thereafter stopper 13 may be raised by pressing button 105a and may be lowered by pressing button 92a.

It will be understood that although any suitable control means such as one operated by an air motor may be used to control the hydraulic system providing such alternative control means permits the operator freedom of movement so that he may observe the pouring, and also providing that such control means rapidly and positively actuates the hydraulic valve so that the stopper will be immediately responsive and close rapidly and firmly, the described electrical control is of unusual advantage in portability, reliability and promptness of response.

It will be appreciated from the foregoing that the apparatus of this invention overcomes all the disadvantages of prior devices and fulfills the objects set forth above.

By means of the hydraulic system employing the substantially non-compressible fluid the stopper can be moved to and maintained at any desired position within its normal operative range and can be rapidly and easily adjusted for the pouring of each successive ingot by means of the valve 60. To shift the stopper upward or downward, the operator need merely depress the corresponding one of the switch buttons 92a, 105a; so long as the selected button is depressed (closing its contacts, Fig. 5), the piston and stopper will move in the corresponding direction, but will come to a halt promptly upon releasing the button, i. e. at the end of the desired change in amount of stopper opening. As explained above, the neutral position of the valve 60 then permits the hydraulic cylinder to hold the stopper in the selected position. If a further or opposite change in stopper opening is desired, an appropriate switch button is again utilized in the same way. In all cases the operator can readily govern the length of time or the number of times that he pushes the button, by direct observation of the metal stream.

Conveniently the switches 92 and 105 are of spring-return type, i. e. including spring means which keep the contacts open except during the interval that the button is actually held down. Although the off-on switch 77 can also be of the same type if desired, it is preferably a two-position switch, for example, including toggle or other means whereby a momentary push shifts the contacts to

closed position where they remain (upon release of the button) until a second momentary push restores them to open position. It will be noted that the switch 77 not only controls the dump valve 85 but also exercises control of the stopper-shifting switches, in that the circuits of the solenoids 72 and 73 extend through the contacts 78, 80 and the valve 60 therefore cannot be moved from neutral position unless switch 77 is closed. By opening switch 77, as in an emergency, the entire system is biased on the side of safety; for example, the up solenoid then cannot be energized to keep or displace the valve 60 in a position where hydraulic fluid might have any tendency to raise the stopper, while the opening of the dump valve and consequent relief of both piston chambers leaves the stopper free for manual operation, and if it is of heavy construction, then with at least a tendency to move closed under its own weight.

In addition, the operator who controls the stopper by means of the portable switch box 117 is free to move about on the platform 42 so that he may accurately observe and determine when the ingot has reached the desired height in the mold and stop the pouring rapidly and positively.

The invention achieves the object of providing a convenient portable apparatus for controlling the ladle stopper by which the operator may move out of danger from the smoke, fumes, steam and splashing metal during the pouring and still have control of the power means for the stopper.

Furthermore, it will be appreciated that the invention fulfills the object of providing an apparatus which provides a safe, positive and selective power control system which can be operated with a minimum of effort and at the same time does not require cumbersome equipment and attachments. The apparatus of this invention can be installed on existing equipment and can be quickly connected or disconnected. For example, when not in use the cylinder 51 may be readily removed from the slide barrel 26 and stored on the platform 42. The hose lines 57 and 58 may be disconnected from the cylinder at the breakaway couplings 148 and the hose lines reeled up to the crane cab 116. Also, the switch box 117 may be taken up into the crane cab by a reel on the cable 118.

In the event of an emergency such as may occur when the nozzle or the stopper breaks, the breakaway couplings may be pulled free with a single sharp pull on the hoses and the ladle may be moved out to the pits where the steel may be permitted to drain from the ladle without damage to the equipment or danger to the operating personnel.

If there is failure of electric power to the system, the dump valve 85 will open so that stopper may be closed by manually operated lever 41 and associated linkage to prevent the loss of steel.

In accordance with the provisions of the patent statutes, I have herein described the principle of operation of the invention, together with the elements which I now consider the best embodiments thereof, but I desire to have it understood that the structure disclosed is only illustrative and the invention can be carried out by other means. Also, while it is designed to use the various features and elements in the combinations and relations described, some of these may be altered and modified without interfering with the more general results outlined.

Having thus described my invention, I claim:

1. In a ladle pouring apparatus having a bottom pour nozzle, a stopper for said nozzle in the ladle, and a stopper linkage means outside the ladle, connected to the stopper for raising and lowering it, a power control apparatus, comprising, a hydraulic power means, means connecting the hydraulic means to the stopper linkage means, valve means for the hydraulic means for selectively directing flow of substantially non-compressible fluid in the hydraulic means to raise or lower the stopper, and electrical control means for the valve means, said electrical control

means being operable by portable manual switch means, whereby the operator of said switch means may move about freely while observing and controlling the pouring.

2. In a hydraulic power system for operation of a ladle stopper, stopper linkage means, including a fixed guide and a movable member slidably mounted in the fixed guide, removable connection means for a driving device, comprising, a pair of mutually separable elements, one of said elements being a hydraulic cylinder and the other being a piston rod for said cylinder, a hook-shaped bracket on the fixed guide, a clevis fixed to one of said elements having arms spaced apart to receive the bracket, a pin disposed between the arms of the clevis and spaced from the base of said clevis, the pin being adapted to be received in a slot defined by the hook of the bracket, the outer edge of the hook remote from the slot being not more than slightly spaced from the base of said clevis when the driving device is in operative position, a second bracket on the movable member of the linkage means, means for removably connecting the other of said separable elements to said second bracket in operative position, flexible means for conveying fluid to and from the hydraulic cylinder, and breakaway coupling means for removably connecting the fluid conveying means to the hydraulic cylinder.

3. A portable and detachable power control unit for operating a ladle stopper, comprising a double acting liquid operated cylinder, a piston slidably mounted in said cylinder, selecting means adapted for connection to the ends of the cylinder for interrupting flow to both ends for arresting the piston at any one of a multiplicity of selectable positions intermediate the ends of the path of piston travel in the cylinder and for directing flow to a selected end for moving the piston in a selected direction along said path, portable control means adapted to be carried by an operator, extendible flexible connections between said control means and said selecting means, and means on the cylinder and piston for removably attaching same to a ladle assembly in operative relation between the ladle and its stopper mechanism.

4. A portable and detachable power control apparatus for operating a reciprocably movable ladle stopper of a ladle that has such stopper and has a member movable to position the stopper, comprising a double acting liquid operated cylinder, a piston slidably mounted in said cylinder, said cylinder and piston including means for removably attaching them to and between the ladle and its stopper-positioning member to effect displacement of the stopper by displacement of the piston relative to the cylinder, selecting means adapted for connection to the ends of the cylinder for interrupting flow to both ends for arresting the piston at any one of a multiplicity of selectable positions intermediate the ends of the path of piston travel in the cylinder and for directing flow to a selected end for moving the piston in a selected direction along said path,

portable control means adapted to be carried by an operator, extendible flexible connections between said control means and said selecting means.

5. In a ladle pouring apparatus having a bottom pour nozzle, a stopper for said nozzle in the ladle, with stopper linkage means outside the ladle, connected to the stopper for raising and lowering it, and a power control apparatus including power means, means connecting the power means to the stopper linkage means, valve means and control means for the valve means, the improvement comprising, hydraulic power means including substantially non-compressible fluid in the hydraulic means and the valve means including means for selectively directing flow in the hydraulic means for raising or lowering and holding the stopper at a multiplicity of selectable positions for continuously controlling the size of the nozzle opening for regulating the rate of flow.

6. In a ladle pouring apparatus, the combination, with a bottom pour nozzle, a stopper for said nozzle in the ladle, and stopper linkage means outside the ladle connected to the stopper for raising and lowering it, of a portable and detachable power control system adapted for operating the stopper of said apparatus, comprising a double acting liquid operated hydraulic cylinder and a piston slidably mounted therein, valve means, a source of fluid under pressure, a reservoir to receive exhaust fluid, means for connecting the valve means to the source of fluid under pressure and the reservoir, and additional means for connecting the valve means to the ends of the hydraulic cylinder, the valve means including means for interrupting fluid flow at both ends of said cylinder for arresting movement of the piston at any one of a multiplicity of selectable positions intermediate the ends of the path of piston travel and for directing fluid flow to a selected end of said cylinder for moving the piston in a selected direction along said path, control means for actuation by an operator connected to such valve means, and means on the cylinder and piston for attaching same to the ladle apparatus in operative relation between the ladle and the aforesaid stopper linkage means.

7. The apparatus of claim 6, including another valve movable to an open position permitting fluid to be exhausted from both sides of the piston and movable to a closed position preventing fluid being exhausted from both sides.
